[57] CLAIM

The ornamental design for a toy building element, as
shown and described.

DESCRIPTION

FIG. 1 is a top perspective view of a toy building ele-
ment showing our new design;

FIG. 2 is a top plan view thereof;

FIG. 3 is an end elevational view thereof;

FIG. 4 is a side elevational view thereof;

FIG. 5 is an end elevational view of the side opposite

that shown in FIG. 3; and

FIG. 6 is a bottom plan view thereof.
